RAZOR BLADE SCRAPER

Ronald L. Gerson, Newton, and Lawrence A. Caprio,
Whitman, Mass., assignors to Louis M. Gerson Co.,
Inc., Middleboro, Mass.

Filed Dec. 19, 1974, Ser. No. 534,451

Term of patent 14 years

Int. Cl. D7—05

U.S. Cl. D7—181

FIG. 1

FIG. 2

FIG. 3

FIG. 4

FIG. 5

FIG. 6

FIG. 7

FIG. 1 is a top plan view of a razor blade scraper showing our new design;

FIG. 2 is a bottom plan view thereof;

FIG. 3 is a left side view thereof;

FIG. 4 is a right side view thereof;

FIG. 5 is an end view thereof;

FIG. 6 is a front view thereof; and

FIG. 7 is a partial cross sectional view thereof through line 7—7 of FIG. 3 showing the razor blade storage cover raised and the razor blade in its retracted position.

We claim:

The ornamental design for a razor blade scraper, as shown and described.
